UNITED STATES PATENT OFFICE.

JAMES WALKER TODD, OF OSNABURG, OHIO.

FENCE-POST.

SPECIFICATION forming part of Letters Patent No. 704,983, dated July 15, 1902.

Application filed November 22, 1901. Serial No. 83,324. (No model.)

To all whom it may concern:

Be it known that I, JAMES WALKER TODD, a citizen of the United States, residing at Osnaburg, in the county of Stark and State 5 of Ohio, have invented certain new and useful Improvements in Fence-Posts, of which the following is a specification, reference being had therein to the accompanying drawings, forming part of this specification, in 10 which—

Figure 1 is a view in elevation of a section of wire fence mounted upon two of my improved posts. Fig. 2 is a front elevation of the post, partly broken away. Fig. 3 is a partial 15 vertical sectional view therethrough, indicated by the line III III of Fig. 2. Fig. 4 is a cross-sectional view on the line IV IV of Fig. 2. Fig. 5 is a similar view, on an enlarged scale, before the insertion of the attaching-strip.

My invention relates to the class of fence-posts and other similar structures, and refers more particularly to a post composed of clay or other vitreous substance or material 25 adapted to be molded into form and to be burned, especially constructed and adapted for the objects in view and provided with means for securing to the post wire, wire-netting, or other form of fence structure.

Referring to the drawings, the main body portion 2 of the post is molded in suitable dies or forming mechanism into suitable lengths having the cross-section shown in Fig. 5, whereby the post is provided with longitudinal 30 rectangular strips 3, intervening depressions 4, and a V-shaped longitudinal groove 6, which elements preferably extend from one end to the other of the post throughout. On each side of the groove 6 the body portion is 35 molded in the form of longitudinal retaining-lips 7, adapted to project over and hold in place a rectangular strip of wood or other suitable material 8. The alternate inner faces 9 of the recess 6 are opposite to and parallel 40 with each other, so that the normal cross-section of the opening is V-shaped, the point of the V being a right angle, the particular object of which is that it is thus adapted to receive square or rectangular strips of wood 45 and to hold them against removal. An especial advantage of this construction is that

the ordinary rectangular mill-stuff may be used for the strip without subsequent finishing or requiring special shape, as dovetail or other form. The cross-section of the post is 55 well adapted to these forms of strip, and the shape and proportions of the retaining-lips 7 are such as not to materially vary the general equilateral form of the post, and by forming the groove so that the inner walls 9 60 converge toward the center and the outer walls 9 extend in an opposite direction the socket is adapted to receive and hold the strip in such a position that only one of its four corners is exposed, the main body portion of it being embraced within the post, 65 securely holding it therein and protecting it from the weather. If desired, this outer corner may be rounded or squared, as indicated at 10 in Fig. 4, thus rendering it more convenient for the attachment of the strands of 70 wire, boards, strips, &c., by means of staples or nails. For the purpose of supporting the strips 8 at the bottom a plug or section 11 of clay is inserted at a convenient point, about 75 the level or slightly above the level of the ground, when the post is in position, such plug or section being inserted after the sectional post is formed in the side and before the post is burned. The strip 8 is inserted at 80 the top of the recess 6 and driven down until it rests upon the plug or step 11, which thus provides a solid rest and also prevents access of moisture to the inner surface of the wood. Any material suitable for making fences may 85 be secured to the strip by nailing, such as wire strands, strips of board, &c.

It will be understood that the posts may be made in any length desired and that the cross-section may also be varied from the 90 specific form shown and described, as well as other changes which may be made by the skilled mechanic, without departing from the invention, and I do not desire to be limited in the accompanying claims to such specific 95 construction as to the outer portion, although the construction of the groove and of the retaining-lips is as I have described it.

The advantages of a post composed of vitreous material or mineral substances, such 100 as fire-clay, are well understood and appreciated, and when made and used in the manner

which I have shown and described my invention is well adapted to provide a post superior in its advantages and novel in its construction over other devices of a generally similar character.

In the process of manufacturing my post after the hollow section has been passed through the dies a strip of wood or other suitable material is inserted through the opening 5 from end to end, which serves to stiffen the plastic section and by which it may be handled and carried with great ease and without danger of warpage or breaking. This strip remains in the section during the drying operation and also during the burning process, in which it will be burned or charred, so that it may be readily removed after the post is taken from the kiln, which operation will greatly facilitate the process of manufacturing and will render a more universal and finished grade of goods.

Having described my invention, what I claim is—

1. A post composed of a mineral substance 25 molded into form and provided with a longitudinal V-shaped groove the angle at the point of the V being a right angle, and having

longitudinal retaining-lips at the outer edges of the groove; substantially as described.

2. A post composed of a mineral substance 30 molded into form and provided with a central longitudinal opening and with a V-shaped longitudinal groove, the angle at the point of the V being a right angle, and having longitudinal retaining-lips at the outer edges of 35 the groove; substantially as described.

3. A post composed of a mineral substance molded into form and provided with a longitudinal V-shaped groove in one of its surfaces, the angle at the point of the V being a 40 right angle, and having longitudinal retaining-lips at the outer edges of the groove, and a stop formed of the same material and constituting a homogeneous portion of the post inserted in the longitudinal groove near the 45 base of the post, for supporting the fence-strip which said groove is adapted to contain; substantially as described.

In testimony whereof I affix my signature in presence of two witnesses.

JAMES WALKER TODD.
